UNITED STATES PATENT OFFICE.

FRANK A. GUILFORD, OF OAK PARK, ILLINOIS, ASSIGNOR OF ONE-THIRD TO WILLIAM J. WILLIAMS, OF LA GRANGE, ILLINOIS, AND ONE-THIRD TO JAMES C. BOWMAN, OF CHICAGO, ILLINOIS.

LIFTING-JACK.

1,323,760.

Specification of Letters Patent.

Patented Dec. 2, 1919.

Application filed February 28, 1916. Serial No. 80,818.

To all whom it may concern:

Be it known that I, FRANK A. GUILFORD, a citizen of the United States, and a resident of Oak Park, in the county of Cook and 5 State of Illinois, have invented certain new and useful Improvements in Lifting-Jacks, of which the following is a full, clear, and exact description.

The invention relates to lifting-jacks and 10 more particularly to those adapted for use in connection with automobiles.

One object of the invention is to provide a lifting jack in which the lifting-standard is provided with an auxiliary adjustable 15 member to adapt the jack to engage the load to be lifted at widely different elevations.

A further object of the invention is to provide an improved locking device for the lifting standard which is simple in construction and in which only a single dog is necessary to hold the standard. A further object of the invention is to provide a lifting jack which can be produced at a low cost. A further object of the invention is to provide 25 a lifting jack which is adapted for operation by a suitably formed removable and double-ended prying-lever.

The invention consists in the several novel features hereinafter set forth and more particularly defined by claims at the conclusion hereof.

In the drawings: Figure 1 is a side elevation of a lifting jack embodying the invention: Fig. 2 is a section taken on line 2—2 35 of Fig. 1. Fig. 3 is a vertical section. Fig. 4 is a vertical section of a portion of the jack, showing the parts in position assumed in lowering the lifting-standard and its load. Fig. 5 is a perspective of the pivot for the 40 locking dog. Fig. 6 is a perspective of the weight for shifting the dog.

The body 8 of the jack has a base 7 and a vertical portion comprising side-walls 9, 10 and 11, all integrally formed. This body is 45 provided with strengthening ribs 12 and openings 14 disposed to attain maximum carrying capacity with the minimum weight. Vertical grooves 15 are formed in the inner face of each of the side walls 9 and 10. The 50 movable lifting member of the jack consists of a standard 16, which has a member 16^a at its upper end to engage the load. This standard fills the space and fits between the side walls 9 and 10 and the end wall 11 of 55 the body. Longitudinal ribs 17 formed on

the side faces of the standard 16 slide in grooves 15 and serve to hold the adjustable member in the body. The body forms a channel, one end of which is open, as at 18, to expose one side of the standard throughout its entire length, and permit adjustable connection of an auxiliary lifting member 19 to that side of standard 16. Openings 16^b are formed in the standard to avoid excessive weight. 65

The lifting member 19 is adapted to be locked in different elevations on the standard 16 for lifting the load when the upper end of the standard, in its lowest position, is too high to be placed under the load. For 70 this purpose, a vertical series of recesses 20 is formed in the exposed face of the standard, these recesses being closed at three sides and open at the exposed side of the standard, so that the auxiliary member may be connected to the standard at any desired elevation while the standard is lowered in the body. This auxiliary member 19 is disposed to project to one side of the body and standard, so it can be projected under the load to 75 be lifted. To render the auxiliary member readily detachable and self-locking, it is formed to extend into a recess 20 and with a lug 21 and a shoulder 22, which form in effect a hook for securing this member to the 80 standard. Each recess 20 is formed with a notch 23 in its top to receive the lug 21. Shoulder 22 is adapted to bear against the side portions of the standard between the recesses 20. The weight of the projecting portion of member 19, as well as the load applied to it, will securely lock said member to the standard 16, the interfit of lug 21 and notch 23 serving to hold the member against 85 outward movement. To adjust member 19, 90 it is only necessary to swing its outer end upwardly to withdraw lug 21 from notch 23 and move the member laterally to unhook and release member 19. Reverse movement will put the member into interlocked relation with any of the recesses 20. 95

The device for latching or locking the standard consists of a dog 27 disposed in the upper portion of the body 8 adjacent the inclosed side of the standard. This dog is 105 formed with a tooth 28 adapted to enter the notches in one side of the standard. These notches and the standard-portions between them form a rack 29. Above the tooth 28, the dog is formed with an abutment 30 110

adapted to engage the standard and limit the inward movement of the dog. Dog 27 is fitted on a polygonal central portion 31 of a spindle 32 which extends laterally through the body and is pivotally sustained therein, being provided with a reduced cylindrical bearing-portion 33 fitting in a corresponding opening in one side of the body and a larger cylindrical bearing portion 34 in a corresponding opening in the other side, and a head 35 at one end. Outside of the bearing-portion 33, the spindle is provided with a reduced terminal 36 which forms a pivot for a weighted arm 37. A lug 38, formed on the terminal 36 and an arcuate slot 39 in the weighted arm, into which said lug extends, provide a lost-motion connection between the weight and the dog which is secured to rock with the spindle by the polygonal portion 31, so that the weight may be shifted either into position at one side of the axis of the spindle to force the dog into engagement with the standard, as shown in full lines in Fig. 1, or into position at the other side of said axis, to normally hold the dog away from the standard, as indicated in Fig. 4. The terminal 36, after the weighted arm has been applied thereto, is upset slightly or riveted so that it will hold the pin and the weighted arm in connected relation to the body 8.

The invention is designed to utilize the rack 29 for the reception of a removable prying lever 40. An angular end 41 is formed on each end of the lever and the terminal 42 of each angular portion is adapted to be inserted between a fulcrum-shoulder 43 on the body and into the superjacent recess of rack 29.

The purpose in angling the end-portion of the lever is to render the lever operative when its central portion is at a convenient elevation above the ground. During a lifting operation, the weight for the locking dog will be in position shown in Fig. 1, so the dog will be yieldingly pressed into engagement with the rack 29. By lowering the outer end of this lever, when its other has thus been inserted, the standard may be raised sufficiently to cause the tooth 28 of the dog 27 to pass into the next notch and thus lift the standard one step. This may be repeated as often as desired, the lever terminal being withdrawn at the end of the lifting operation and inserted into the next lower notch of the rack. This prying lever also serves to lower the standard step-by-step. To lower the load, the weighted arm 37 is shifted into position indicated in Fig. 4, so that its force will be applied to disengage the dog from the standard. This weight, however, is insufficient in itself to rock the dog when it sustains the weight of the standard or the load, and consequently, this weight will not release the dog from the

standard until the dog is relieved of the weight of the standard and the load. To lower the standard, one of the terminals of lever 40 is inserted into the notch of the rack 29 adjacent abutment 43 and in position indicated in dotted lines in Fig. 4 and its outer end is then depressed slightly to relieve the tooth 28 of dog 27, whereupon the weighted arm 37 will swing the dog into position shown in full lines in Fig. 4. Next, the outer end of lever 40 will be permitted to be raised slowly by the load which will cause the operative angular portion of the lever to strike a resilient strip 44 on the tail 45 of the dog to force the tooth 28 into the recess of rack 29 above the one last engaged by the tooth, whereupon the weight of the standard and the load will be applied to the dog, which will be held in position with sufficient force to prevent its shift by the weight. To further lower the standard, the operation of the lever 40 will be repeated, its terminal 42 being inserted in the notch, which has been last lowered into operative relation adjacent abutment 43. Resilient strip 44 serves to guide the lever terminal to the proper notch in the rack and also permits yielding pressure of the lever to be applied thereto to insure its timely engagement with the rack in the lowering operation.

The invention thus exemplifies a lifting jack which is simple in construction and can be produced at a low cost. A single dog and rack serve to successively lock the standard at different elevations, both during the lifting and lowering operations. The prying lever wholly removable from and connectible to the jack is utilized to effect both raising and lowering operation and avoids the necessity of a pivoted socket. By employing a lever provided with an operative terminal or portion at both ends, provision is made for its use in event one end should become broken. The adjustment between the auxiliary engaging member and the standard may be readily effected. The device in its entirety is light in weight.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a lifting jack, the combination of a body, a standard slidably held in the body, means for raising the standard, the latter having recesses formed in one of its sides and integral walls at the back, above, below and at the sides of the recesses, and an auxiliary supporting member having a hook extension adapted to pass into and removably interlock with either of the recesses.

2. In a lifting jack, the combination of a

body, a standard slidably held in the body, means for lifting the standard step-by-step, the standard having a vertical series of recesses in one of its sides, and an auxiliary lifting member having a hook extension comprising an integral upwardly extending lug and a downwardly extending shoulder, each recess having a notch in its top to receive the lug, the body having abutments 5 for the shoulder, said member being removable and self-holding in the recess.

3. In a lifting jack, the combination of a body, a standard slidable in the body and provided with a rack, a dog for locking the 15 standard, means on the dog for shifting it either away from or into the rack and an operating lever provided with means for engaging the rack to lift it step-by-step and having means thereon for engaging the dog 20 and forcing it into the rack in lowering the standard.

4. In a lifting dog, the combination of a body, a standard slidable in the body and

provided with a rack, a dog for locking the standard, a weight on the dog and having a lost motion connection therewith for shifting it either away from or into the rack and an operating lever provided with means for engaging the rack to lift it step-by-step and having means thereon for forcing the dog into the rack when the lever 25 is operated to lower the standard.

5. In a lifting jack, the combination of a body, a standard having a vertical rack thereon slidably held in the body, a dog for 35 engaging the rack, a prying lever having at each end an inclined portion provided with a terminal for engaging the rack and being completely detachable from the body, said portions being oppositely inclined and of 40 substantially the same shape so that either end of the lever may be used to operate the standard, and a fulcrum abutment for the lever on the body.

FRANK A. GUILFORD.
